CLAIM

The ornamental design for a packaging box, as shown and described.

DESCRIPTION

FIG. 1 is a front, top and right-side perspective view of a first embodiment of a packaging box, showing my new design; FIG. 2 is a front, top and right-side exploded view thereof, FIG. 3 is a back, bottom and left-side exploded view thereof, FIG. 4 is a front elevation view thereof, FIG. 5 is a right-side elevation view thereof; FIG. 6 is a top plan view thereof, FIG. 7 is a bottom plan view thereof, FIG. 8 is a bottom plan view of the upper portion thereof, shown separately to show aspects of the design that are not visible when combined; FIG. 9 is a top plan view of the lower portion thereof, shown separately to show aspects of the design that are not visible when combined; FIG. 10 is a front, top and right-side perspective view of a second embodiment of a packaging box, showing my new design; FIG. 11 is a front, top and right-side exploded view thereof, FIG. 12 is a back, bottom and left-side exploded view thereof, FIG. 13 is a front elevation view of thereof; FIG. 14 is a right-side elevation view thereof; FIG. 15 is a top plan view thereof, FIG. 16 is a bottom plan view thereof, FIG. 17 is a bottom plan view of the upper portion thereof, shown separately to show aspects of the design that are not visible when combined; and, FIG. 18 is a top plan view of the lower portion thereof, shown separately to show aspects of the design that are not visible when combined.

(Continued)

A back view and a left-side view are omitted because they are identical with the front view and the right-side view, respectively. The parts shown by means of broken lines in the packaging box of FIG. 10 to FIG. 13 are part of the claimed design and indicate the perforation lines.

The broken lines in FIGS. 8, 9, 17 and 18 depict portions of the packaging box that form no part of the claimed design.
